TEST CIRCUIT

Percy N. Burrows, St. Albans, and Norman E. Lockwood, Flushing, N. Y., assignors to Socony-Vacuum Oil Company, Incorporated, New York, N. Y., a corporation of New York

Application February 10, 1942, Serial No. 436,198

2 Claims. (Cl. 175—329)

This invention relates to an electrical circuit including a condition responsive element together with means for timing the duration of a desired condition and means actuated thereby to operate suitable controls in the event the desired condition is of improper duration. Specifically, the invention is concerned with a purge timing relay or means for determining whether a flow of gas is of sufficient duration and space velocity and for insuring that no deleterious results shall follow insufficient gas flow.

In a specific embodiment in which the apparatus of this invention has been employed, it is associated with electrical controls of a plant for the catalytic cracking of heavy hydrocarbon oils to lighter products such as gasoline. A granular catalyst is disposed in each of a plurality of closed vessels, hereinafter called "cases," provided with means to supply and withdraw fluid products. The cases are also equipped with heat exchange elements having no bearing on the present invention.

The granular catalyst is such that, after operation "on-stream," that is, passing oil vapor therethrough for treatment, for a certain period of time, the catalyst becomes contaminated with carbonaceous by-products of the treating operation to such an extent that its efficiency is seriously reduced. A pre-heated oxidizing gas, such as air, is then passed through the catalyst to burn off the deposits of carbonaceous matter and restore the efficiency of the catalyst. This step is known as regeneration. In commercial operation, several cases, usually in groups of three, are operated simultaneously in order that a continuous stream of hydrocarbon vapors may be supplied to the battery of cases and regeneration in one will be concurrent with an on-stream period of at least one other, the cases each operating on a predetermined cycle of alternate on-stream and regeneration periods. In a typical installation, a complete cycle occupies a period of about 40 minutes.

As will be readily apparent, great caution must be exercised to avoid formation of explosive mixtures in the cases (which operate at temperatures upwards of 750° F.) when changing from on-stream to regeneration and vice versa. This is generally accomplished by a step of purging with inert gas such as steam at each change-over, with or without an additional purging by application of a vacuum to the case. Obviously, it is of greatest importance that the purging be of an extent not less than a minimum which will render the atmosphere in the case inert to the ma- 55

terial to be introduced. Many known means have been tried to insure that the steam purging, or purging with other inert gas such as products of combustion, shall be conducted with a minimum space velocity of purging medium for a minimum period of time. None of the known devices has proven satisfactory and we have developed a novel relay controlled circuit to accomplish that purpose.

10 The specific novel circuit of the invention illustrated here is designed for use in connection with the present electrical controls on catalytic cracking plants. In the particular installation for which the specific circuit described was designed, operation of the plant is by means of automatic electrical controls. A battery of three cases are operated by a master cycle timer of the EM-5 and EM-8 types described in the General Electric Bulletin GEC-2838 which comprises a plurality of successive conductive segments connected to electrical operating equipment and a contacting element moving over and successively energizing the segments. Each of the valves for controlling conduits to supply and withdraw hydrocarbon vapors, regenerating air, purging medium, etc., to each case, is operated by an electric motor placed in operation through a suitable relay energized from the cycle timer. Associated with each valve there is also a test contact which opens when the valve reaches an extreme position, either open or closed. One segment, spaced to provide a suitable time interval after each valve operating segment, is connected for supplying a test current to said test contact. Suitable relays are provided to shut down the battery in the event the test current flows, indicating an improperly operated valve.

15 20 25 30 35 40 45 The circuit of the present invention provides metering means for determining whether the purge gas flow is equal to or greater than a predetermined minimum both in space velocity and time of flow. Means are provided responsive to said metering means for preventing valve operation in the battery and for setting in operation the alarm and shutdown mechanisms of the cycle timer in the event these minima are not met.

The nature of the invention will be apparent from the following description when considered in connection with the annexed drawing, where- 50 in:

Figure 1 is a schematic wiring diagram of a specific embodiment of the invention; and

Figure 2 is a diagrammatic elevation of one face of the purge timing relay.

The form of the invention illustrated in Figure

1, includes as elements of primary importance a fluid flow responsive switch 10, of known design and a timing relay indicated generally at 11. The flow responsive switch 10 is adjusted to close upon the flow of steam in a conduit 12, reaching a predetermined minimum. The timing relay comprises a non-magnetic disc 13 driven by a synchronous motor 14', through suitable reduction gears to provide a desired speed and carries four permanent magnets 14, 15, 16 and 17, spaced angularly thereabout. Two of the magnets, namely, 14 and 15, are mounted on one face of the disc 13 near the edge thereof and in a corresponding position spaced from the disc on the same side is a switch 18, adapted to close responsive to magnetic attraction from a magnet 14 or 15 adjacent thereto. Suitable switches for this purpose are mercury contact switches which are spring biased to open position but are supplemented by magnetic material and arranged to be drawn to closed position by one of the magnets 14 and 15. Permanent magnets 16 and 17 are mounted on the other face of the disc 13 and spaced inwardly from the edge a substantial distance. A switch 19, similar in structure and operation to switch 18 is mounted on the side of disc 13, corresponding to and arranged for closing by magnets 16 and 17.

Current for operation of the timing relay is supplied from a usual source of 110 v., 60 cycle current through two poles of the three-pole switch 20 which is mechanically interlocked with a shunt switch 21, the purpose of which will appear hereinafter. The switches 20 and 21 are interlocked in such manner that one is open and the other closed at all times. This is necessary for when the unit is off stream and at such times when the cases are being purged by manual controls, the manual three pole switch 20 should be in "off" position so that the relays will not function and manual shunt switch 21 should be in the "on" position to permit electrical operation of the motor valves which control the purging. One lead of the supply current passes to limit switches (not shown) by line 22. These limit switches are of conventional motor valve operated type and are sold on the market under the designation of "Type #12 motor valve operated limit switches." If certain of the limit switches are closed, the current may flow through a pole 4' of the test relay to the flow responsive switch 10 and thence to motor 14 completing the motor energizing circuit. Looking now to operation of the battery of cases; purging of a particular case will take place when the cycle timer has operated suitable valves. The line 32 is connected with a certain series of limit switches in each case of the battery, with the three series in parallel. When the valves of any of the three cases are in proper position for purging, the circuit, including line 22 through that case, will be closed. Now, if there be a sufficient flow of steam through the header 12 common to all three cases, switch 10 will close and the motor circuit is complete, causing rotation of disc 13 carrying the permanent magnets. As the disc rotates clock-wise, magnet 16 will come into position to actuate switch 18 and supply current through pole 3 of the main relay to move the armature thereof downward by energizing an actuating coil 23. (It may be noted here that, for purposes of simplicity, the two actuating coils of each of the three four-pole relays designated as "Main relay," "Test relay" and "A relay" are shown

5 schematically with arrows indicating the direction in which they move the armatures.)

The above noted movement of the main relay completes a holding circuit through pole 2 thereof, thus maintaining the motor 14' in operation; simultaneous closing of a circuit through pole 1 completes operating circuits of the test relay and the A relay through poles 3' and 2'' and coils 24 and 25, respectively, causing the armatures of these relays to be moved downward. This opens the circuit, including switch 10, through pole 4' and opens a test circuit through pole 1', the purpose of which will appear hereinafter. A circuit is now provided through pole 3'' including the coils 26 and 27 for resetting the test and A relays and upon supply of current through lines 28 and 29, these relays will be reset. A circuit is also closed through poles 1'' and 2' to signal lamp 30. The A circuit through pole 2'' furnishes current for actuation of all the valve motors in the battery and it is apparent that none of these motors may operate except when the armature of the A relay is in the down or closed position.

The disc 13 is still rotating by reason of the holding circuit through pole 2 and will continue to rotate until magnet 15 reaches operative position and closed switch 18. Thereupon, the circuit through pole 4 and coil 24 will reset the main relay by upward movement of the armature and open the holding circuit, stopping rotation of the disc. The apparatus is designed and connected to the remaining control equipment in the plant to remain in this condition, with the main relay reset and the test and A relays closed until just before time for the next purge operation. Meanwhile, promptly after purging should be complete in accordance with predetermined operation design, a testing current is supplied through lines 32 and 33 from a suitable segment of the cycle timer. If the operation of purging has been sufficient, i. e., if the flow in header 12 has been of sufficient space velocity to maintain switch 10 closed for sufficient time to rotate the disc to position for closing switch 18 before the testing current is applied, pole 1' will be open and the testing current will not flow. If, on the other hand, pole 1' is still closed when the testing current is applied, the cycle timer will alarm and shut down the battery, thus preventing supply of fluids to an insufficiently purged case. This same result is further insured by open pole 2'' in the A relay which renders it impossible to energize the valve motors.

Assuming operation proceeds normally, the cycle timer will approach another segment operating a purging relay. Immediately prior to that segment, is a reset segment for the test and A relays which supplies a current by way of lines 28 and 29. The assembly is then in condition to act with respect to the next purging operation which again must maintain a minimum space velocity over a period sufficient to rotate disc 13 from the position of magnet 15 to that of magnet 17 before a test current is supplied through lines 32 and 33 in order for the battery of cases to continue operation.

If desirable, the battery may be controlled manually, in which case the interlocked switches 20 and 21 are thrown, opening the contacts of switch 20 and closing that of switch 21 to discontinue operation of the purge timing relay and supply the A current for motor operation by shunting out the contacts of pole 2'.

In its preferred form, the purge timing relay includes at least three adjustable magnets, which

may be mounted on arms 34 as shown in Figure 1 and held in adjusted position as shown in Figure 2 by means of washer 35 and nut 36. One of the permanent magnets as shown in Figure 1 in back of the disk 13 may be fixed without affecting adjustability as will be apparent.

Preferably, signal lamps 30 and 37 are also included to indicate the state of the device. Green light 37 is connected in parallel with motor 14' and will be illuminated when said motor is operating. Amber light is in a circuit completed through poles 2' and 1" of the test and A relays, respectively. Illumination of this light indicates that a purge has been satisfactorily completed and that the test impulse through line 33 from the cycle timer will not be followed by alarm and shut-down of the battery.

We claim:

1. In a device of the class described, a substantially constant speed motor, a motor circuit for supplying an energizing current to said motor, a normally open switch in said motor circuit adapted to close responsive to a predetermined minimum flow of fluid in a conduit, means to energize said motor circuit, a test circuit, means to apply an electrical impulse to said test circuit at a first predetermined interval of time after said motor circuit is energized, a circuit breaker in said circuit and means responsive to the rotation

5 of said motor to open said circuit breaker following operation of said motor for a second predetermined interval of time; whereby said test circuit is conditioned to indicate satisfactory operation only if the flow of fluid has been at a rate not less than said minimum for a period of time equal to said second predetermined interval during said first predetermined interval.

10 2. In an apparatus for control of a process requiring flow of a fluid at not less than a predetermined minimum rate for not less than a predetermined minimum time of flow and having a test circuit and means to apply an electrical impulse to said test circuit at a predetermined test interval of time after said flow of fluid is initiated; the combination with said control apparatus of a substantially constant speed motor, a motor circuit for supplying an energizing current to said motor, a normally open switch in said motor circuit adapted to close responsive to said predetermined minimum rate of flow of said fluid in a conduit, means to energize said motor circuit, means responsive to rotation of said motor to condition said test circuit upon rotation of said motor for a period of time equal to said predetermined minimum time.
